[57] CLAIM

The ornamental design for a laundry status display apparatus, as shown and described.

DESCRIPTION

FIG. 1 is a front plan view of the laundry status display apparatus of the present invention;

FIG. 2 is a back plan view of the laundry status display apparatus of FIG. 1;

FIG. 3 is a left side plan view of the laundry status display apparatus of FIG. 1;

FIG. 4 is a right side plan view of the laundry status display apparatus of FIG. 1;

FIG. 5 is a top plan view of the laundry status display apparatus of FIG. 1; and,

FIG. 6 is a bottom plan view of the laundry status display apparatus of FIG. 1.

The broken away section of the power cord is due to indeterminate length.

The broken line showing of the words "RINSE CYCLE" is for illustrative purposes only and forms no part of the claimed design.
